(57) **CLAIM**

We claim the ornamental design for an identification tag for pet, as shown and described.

DESCRIPTION

The patent or application file contains at least one color drawing. Copies of this patent or patent application publication with color drawing will be provided by the USPTO upon request and payment of the necessary fee.

FIG. 1 is a front perspective view of an identification tag for pet showing a new design;

FIG. 2 is a bottom perspective view thereof;

FIG. 3 is a front view thereof;

FIG. 4 is a rear view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is a perspective view showing a state of use being combined with a silicone band and blue color indicates when a LED light is on;

FIG. 10 is a perspective view showing a state of use thereof; and,

FIG. 11 is another perspective view showing a state of use thereof.

The broken lines in FIGS. 9-11 illustrate environmental structure that form no part of the claimed design.
